MOTOR VEHICLE CONTROL

Anton A. Wentzel, Milwaukee, Wis.

Application October 22, 1938, Serial No. 236,445

6 Claims. (Cl. 192—.01)

This invention relates to motor vehicle controls and particularly to improved fuel supply control means therefor.

In driving modern automobiles, the supply of fuel to the motor is practically exclusively under the control of the accelerator pedal so that, insofar as the fuel is concerned, the driving is performed only by the right foot of the driver, the left foot coming into play only on occasions when the clutch is to be released. This condition, particularly in long distance driving, is the cause of serious fatigue on the part of the driver, because the muscles of the right foot and leg are under tension continuously for long periods of time, without interruption or opportunity for relaxation.

Of course many motor vehicles are also equipped with a manually controlled element by which the fuel may be regulated independently of the accelerator pedal, but this element is used only during starting, if at all, and not during driving, because, arranged as at present, its use during driving would be neither convenient nor safe, but would seriously interfere with the important steering function performed by the hands.

An object of the present invention is to provide an improved control system which will assure adequate and convenient control of the fuel supply without requiring continuous use of either foot of the operator and without impairing or interfering with other normal driving functions.

Other more specific objects and advantages of the present invention will appear, expressed or implied, from the following description of an illustrative embodiment thereof.

In the accompanying drawing:

Figure 1 is a view in perspective diagrammatically illustrating a motor vehicle control system embodying the present invention.

Fig. 2 is a similar view illustrating other operating positions of parts shown in Fig. 1.

Fig. 3 is a fragmentary plan view illustrating a preferred positional relation between the steering wheel and control lever shown in the other figures.

The control system selected for illustration includes a conventional carburetor, partially indicated at 10, with its throttle valve 11 and lever 12, the lever 12 being equipped with the usual set screw 13 for coaction with a conventional stop 14 to determine the idling position of the valve 11. The lever 12 is shown connected, through a link 15 and bellcrank 16, with push rod 17 which

is under the control of a conventional accelerator pedal (not shown) by which the throttle valve 11 may be rocked to regulate the rate of flow of fuel through the carburetor in the usual manner.

In this instance, the bellcrank 16 is also connected through a push rod 18 with an arm 19, depending from and fixed to a horizontal rock shaft 20 mounted in appropriate brackets 21 and 22 upon the front of the motor vehicle dash 10 board 23. The rock shaft 20 also carries an upwardly inclined arm 24 whose upper end has a swivel connection 25 with a block 26.

A horizontal rod 27 is lengthwise moveable within the block 26. The rod 27 carries at its forward end a stop member 28, fixed thereto, and at its rear end the rod is fixed to one end of a steel wire 29 which passes through an appropriate guide tube 30 and is attached at its other end to an arm 31 carried by a rock shaft 32 mounted upon a conventional steering wheel post 33. The guide tube 30, which extends through the dash board 23 and is appropriately fixed to the conventional panel 34, is preferably packed with grease which offers substantial resistance to lengthwise movement of the wire 29 within the tube.

The rock shaft 32 preferably extends upwardly along the steering wheel post 33 to a point adjacent the under side of the steering wheel 35 and carries at its upper end a control lever 36 fixed thereto. This lever 36 may assume various forms, but preferably extends to a point adjacent but below the rim of the wheel where it may be conveniently manipulated by a finger on the left hand of the driver without requiring withdrawal of that hand from gripping engagement with the wheel, and where that hand may pass with the wheel over the lever without striking the lever.

The arrangement is such that, when the control lever 36 is in the position shown in Figs. 1 and 3, the wire 29 and rod 27 are advanced so that the block 26 and the above described connections between it and the throttle valve 11 normally assume a valve closing or idling position. However, the fact that the block 26 is slidable on the rod 27 permits movement of those connections and of the valve in response to actuation of the rod 17 in response to actuation of the accelerator pedal, and without disturbing the position of the control lever 36. It is thus possible to place the supply of fuel to the motor under the control of the accelerator pedal whenever

driving conditions warrant control in this manner.

However, upon depressing the control lever 36 toward or through the full line position of Fig. 2, the wire 29 and rod 27 are retracted in such manner that the stop 28 engages and forces the block 26 rearwardly, thereby rocking the shaft 20 and arm 19 in such direction as to advance the push rod 18 and thus open the throttle valve 11 to an extent dependent upon the extent of movement of the control lever 36. The control lever 36 and the rod 27 are yieldably retained in any position to which they are thus shifted by the frictional resistance to movement of the wire 29 in the guide tube. The throttle valve 11 may thus be adjusted, by manual adjustment of the control lever 36, to supply sufficient fuel to the engine for driving at any desired speed, such as thirty, forty, or fifty miles per hour, and when thus driving over long stretches of fairly level roads, he may remove his foot entirely from the accelerator pedal.

It will of course be understood that when driving under control of the lever 36 in the manner just described, the fuel supply may be momentarily increased by actuation of the accelerator pedal, if the condition of the road requires, without disturbing the set position of the control lever 36, and when the accelerator pedal is again released the throttle valve will return to the position determined by the position to which the control lever 36 has last been set.

Should the clutch be opened while the control lever 36 is in the depressed position of Fig. 2, with the throttle valve open or partially open, it is obvious that the motor would race. To avoid this objectionable condition, provision is made for effecting automatic return of the control lever 36 to the idling position of Fig. 1 whenever the clutch is opened. In this instance, mechanism for this purpose includes a second rock shaft 37, provided on the front of the dash board 23 and extending from the vicinity of the rock shaft 20 to the vicinity of the clutch pedal lever conventionally indicated at 38.

Shaft 37 carries at one end an arm 39 connected to the clutch lever 38 through a normally slack connection including a link 40 and coil spring 41. The shaft 37 also carries at its other end an arm 42 connected to the stop 28 on rod 27 through appropriate linkage 43. The arrangement is such that the normal slackness in the spring 41 and link 40 permits free rocking of the shaft 37 in response to adjustment of the rod 27, wire 29, and control lever 36, but whenever the clutch lever 38 is depressed to open the clutch, the spring 41 is thereby tensioned in a manner to rock the arm 39, shaft 37, and arm 42 in a direction to force the rod 27 forwardly and thus automatically return the control lever 36 and throttle valve 11 to the idling position of Fig. 1.

It will thus be noted that whenever the clutch pedal 38 is depressed to open the clutch, for the purpose of bringing the vehicle to a stop or otherwise, the control lever 36 and throttle valve 11 return automatically to an idling position, from which position the control lever may, upon restarting the vehicle, be manually adjusted to effect the acceleration desired and thereby avoid an objectionable jerky start which would otherwise result if the control lever 36 had not been returned to the idling position.

Provision is also made for automatically returning the control lever 36 to idling position whenever the brake is applied. The mechanism

shown for this purpose includes a third arm 44 carried by the rock shaft 37. In this instance the arm 44 is connected, through an appropriate link 45, with a trip lever 46 whose lower end 47 extends downwardly into the path of travel of the brake pedal lever conventionally indicated at 48. The lever 46 is shown rockably supported intermediate its ends upon a suitable bracket 49 mounted on the dash board 23 above the brake lever 48. The lower end 47 of the lever 46 is normally spaced from the brake lever 48 so that it does not interfere with free rocking of the shaft 37, but whenever the lever 48 is depressed to apply the brakes it strikes the lower end 47, causing the same and the shaft 37 to rock in a direction to automatically return the control lever 36 to the idling position in the manner above described.

The lever 46 is preferably adjustable so as to effect contact with the brake lever 48 at variable points in the stroke of the brake lever, and in that manner compensate for variation in the brake lever action resulting from brake adjustments. For this purpose the end portion 47 of the lever 46 is adjustably connected thereto through appropriate means, such as clamp screws 50 carried by the lever 46 and engaged in a longitudinal slot in the end portion 47, so that the latter may be adjusted lengthwise as desired. The automatic return of the control lever 36 may thus be synchronized with the braking action regardless of brake adjustments.

Various changes may be made in the embodiment of the invention hereinabove specifically described without departing from or sacrificing the advantages of the invention as defined in the appended claims.

I claim:

1. In a control system for a motor vehicle having a steering wheel and a control pedal, the combination of a manually adjustable element mounted adjacent said wheel, means yieldably retaining said element in various positions of adjustment, a fuel regulator, means responsive to adjustment of said element for adjusting said regulator, means including an independently moveable element operable on said last named means to further adjust said regulator without disturbing the position of said first named element, and means responsive to actuation of said pedal for returning said first named element and said regulator to idling position.

2. In a control system for a motor vehicle having a control pedal, the combination of a fuel regulator, means including an element manually adjustable to adjust said regulator, means yieldably retaining said element in various positions of adjustment, means including another element adjustable to regulate said regulator without disturbing the position of said first named element, and means responsive to actuation of said pedal for returning said first named element and said regulator to idling position.

3. In a control system for a motor vehicle having two control pedals, the combination of a fuel regulator, a manually adjustable element, means yieldably retaining said element in various positions of adjustment, means responsive to adjustment of said element for adjusting said regulator, means including an independently moveable element operable on said last named means to further regulate said regulator without disturbing the position of said first named element, and means responsive to actuation of either of said

pedals for returning said first named element and said regulator to idling position.

4. In a control system for a motor vehicle having a clutch pedal, a manually adjustable element, means for yieldably retaining said element in various positions of adjustment, a fuel regulator, means responsive to adjustment of said element for adjusting said regulator, an independently moveable element operable on said last named means to further adjust said regulator without disturbing the position of said first named element, and means responsive to actuation of said clutch pedal for returning said first named element and said regulator to idling position.
5. In a control system for a motor vehicle having a steering wheel and a brake pedal, a manually adjustable lever having a portion disposed adjacent the rim of said wheel, means for yieldably retaining said lever in various positions of adjustment, a fuel regulator means responsive to adjustment of said lever for adjusting said regulator, an independently moveable element operable to further adjust said regulator without dis-

turbing the position of said lever, and means responsive to actuation of said brake pedal for returning said regulator and said lever to idling position.

6. A fuel control system for a motor vehicle having a steering wheel and control pedal, said system comprising the combination of a fuel regulator, a control lever adjacent the rim of said wheel, a rod moveable in response to movement of said lever, a block moveable relative to said rod and connected to said fuel regulator, means moveable with said rod and operable on said block to actuate said block and regulator in one direction, means operable to further move said block and regulator in the same direction without disturbing the position of said rod and lever, means for yieldably retaining said lever and rod in various positions of adjustment, and means responsive to actuation of said control pedal for returning said lever and regulator to idling position.
